UNITED STATES PATENT OFFICE.

CLINTON M. WOLFE, OF COEBURN, VIRGINIA, ASSIGNOR OF ONE-FOURTH TO EMORY HOGE MILLER, ONE-FOURTH TO JOHN A. NEWBERRY, AND ONE-FOURTH TO WILLIAM R. CULBERTSON.

CHURN.

1,220,923.

Specification of Letters Patent Patented Mar. 27, 1917.

Application filed January 23, 1917. Serial No. 143,923.

To all whom it may concern:

Be it known that I, CLINTON M. WOLFE, a citizen of the United States of America, residing at Coeburn, in the county of Wise and State of Virginia, have invented new and useful Improvements in Churns, of which the following is a specification.

The present invention relates to improvements in churns, and particularly to certain novel combinations and arrangements of the operating and actuating mechanisms of the device. The primary object of the invention is to improve the construction of churns by providing a blade or paddle device which is efficient in operation, durable, and at the same time may be operated with facility and comparatively slight expenditure of energy to agitate the cream in order to make the fat-globules unite to form butter. The invention 20 consists essentially in certain novel combinations and arrangements and structures of the dasher blades and their operating devices whereby the action of the churn is greatly enhanced and increased.

25 In the accompanying drawings I have illustrated one complete example of the physical embodiment of my invention, constructed according to the best mode I have so far devised for the practical application 30 of the principles of my invention, and this form of the invention has already proven highly satisfactory in actual use.

Figure 1 is a side elevation of the complete churn, parts being shown in section, illustrating an apparatus made according to my invention.

Fig. 2 is a side elevation, at right angles to the parts shown in Fig. 1, depicting the dasher and connections.

40 Fig. 3 is a detail, fragmentary, view showing the construction of the slidable hinge joint of the dasher.

Fig. 4 is a fragmentary view showing, partly in section, the connection between the 45 pitman rod and the link.

Fig. 5 is an enlarged sectional detail view showing the connection between the stationary hinge joint and the supporting spindle of the churn.

50 Fig. 6 is a sectional view on line 6—6 of Fig. 2.

In the preferred embodiment of my invention as shown in the drawings I utilize the usual barrel or receptacle 1 which may be 55 of suitable or desirable material, together

with the customary frame 2 upon which the actuating and operating mechanisms are supported.

Within the barrel or receptacle 1, a supporting spindle 3 is located and fixed in a suitable manner, as in the seat 4, and the spindle projects vertically upward through the barrel as indicated.

As will readily be seen the spindle 3 is designed to support the dasher of the churn, 65 which dasher may be described as comprising a set, or two pairs of hinged blades designated as 5, 6, 7, 8, which are hinged together in pairs as at 9 and 10, and then the pairs are hinged together at 11 and 12. The 70 hinge joint 9 is a stationary one, the pin 13, 13, of the hinge, being passed through opening 15 of the spindle 3 and having at one end handle 13' and at its other end a cotter pin 13a. There are three of these openings 15 75 illustrated in the drawings, but the number may be increased or decreased as desired, so that the dasher may be adjusted in its altitude with relation to the bottom of the churn barrel. The hinges 11 and 12 are folding 80 hinges so that the upper and lower pairs of blades may be folded outwardly at the center of the dasher, (see dotted lines Fig. 2) as the churn is operated. The hinge joint 10 at the upper end of the dasher between 85 the two blades 7 and 8 is a slidable joint, and to accomplish this purpose the hinge pins 16 of this joint are seated in diametrically arranged recesses or notches 17, 17, in the bushing or sleeve 18, of a vertically reciprocable link 19 which is operated by means of the pitman 20. The joint between the link 90 and its pitman is adjustable in order to lengthen or shorten the reciprocating parts. Thus, the lower end of the pitman is screw 95 threaded as at 21 and a turn buckle 22 is threaded thereon, a lock nut 23 being utilized to prevent turning of the buckle. The buckle is provided with a bifurcated end and the two arms or forks thereof, as 24, 25 100 are perforated at their extremities for passage of the locking pin 26 carried at the end of the spring arm 27 which is attached to the buckle at 28. The upper end of the link is perforated as at 29, 29, 29, for the 105 passage of the pin 26, and by using different ones of these perforations, a long or shorter connection may be provided between the link and pitman.

The link reciprocates vertically through a 110

perforated transversely arranged horizontal brace arm 30 which guides the link, and also holds the spindle 3 steady and stable. On its under surface the guide bar or arm 30 is recessed as at 31, adjacent the guide opening 32, so that the head of the spindle is enclosed therein and the spindle held rigid between this brace or guide arm and the bearing block or seat 4 on the bottom of the 10 churn barrel.

The guide arm 30 is pivoted in the frame at 33, and extends across to the opposite side of the frame where it may be latched as at 34 to hold or retain it in operative position, and a pivoted latch 30' is used to guide the link 19.

Reciprocating movement is imparted to the pitman through the crank shaft 35 journaled at the upper end of the frame and the pinion 36 on this shaft by means of the gear 37 and handle 38, supported in the frame and meshing with the pinion.

The blades of the dasher are provided with a suitable number of openings 39 25 through which the cream is passed as the folding dasher is opened and closed. The operation of the apparatus will be evident, and it is hardly necessary to give a detailed description. However it will readily be seen 30 that when the crank shaft 35 is rotated

through the gears 37 and 36, the pitman and its link are caused to reciprocate through the brace 30, with the result that the blades of the dasher are caused to fold and unfold on their hinges with a contracting and distending movement as indicated in Fig. 2. The cream is thus forced through the openings 39 in the blades and port 39' between blades 8 and 6 and 7 and 5, and the action of the churn has the desired result.

Alterations and changes within the scope of my claim may be made without departing from the spirit of my invention, and such colorable changes are contemplated.

What I claim is:

The combination with the supporting frame, the receptacle and operating means, of a fixed spindle having a series of openings therein, a pair of oppositely located blades having a hinge pin passed through one of the openings in the spindle, a pair of blades hinged to the free ends of the first pair of blades, a pitman connected to the operating means and a link connected to the pitman, a bushing integral with the link and adapted to slide on the spindle, and a hinge joint between the second pair of blades and said bushing.

In testimony whereof I affix my signature.
CLINTON M. WOLFE.
